UNITED STATES PATENT OFFICE

160,053

ORNAMENT FOR AN AUTOMOBILE BODY

Harry T. Bannister, Huntington Woods, Mich.

Application April 7, 1950, Serial No. 9,032

Term of patent 7 years

(Cl. D14—6)

To all whom it may concern:

Be it known that I, Harry T. Bannister, a citizen of the United States, residing in the city of Huntington Woods, county of Oakland, and State of Michigan, have invented a new, original, and ornamental Design for an Ornament for an Automobile Body, of which the following is a specification, reference being had to the accompanying drawing, forming part thereof, in which:

Fig. 1 is a front elevational view of an ornament for an automobile body, showing my new design;

Fig. 2 is a top plan view thereof;

Fig. 3 is a side elevational view thereof;

Figs. 4 and 5 are cross sectional views taken on the lines 4—4 and 5—5 of Fig. 1; and

Fig. 6 is a perspective view of the ornament

for an automobile body of my invention, the broken line showing therein of a portion of the automobile being for illustrative purposes only.

I claim:

The ornamental design for an ornament for an automobile body, substantially as shown and described.

HARRY T. BANNISTER.
